BY

John C. Sappington ^{DT} ATTORNEY

1,004,358. DRYING APPARATUS. Enos A. Bronson, Newburgh, N. Y. Filed Aug. 24, 1910. Serial No. 578,734.

To all whom it may concern:

Be it known that I, Enos A. Bronson, a citizen of the United States, and resident of Newburgh, in the county of Orange and State of New York, have invented certain Improvements in Drying Apparatus, of which the following is a specification:

This invention relates to certain improvements in drying apparatus, and more particularly in that class of such apparatus, which are especially designed and adapted for use in drying sand and the like, and the object of the invention is to provide an apparatus of this general character of a simple and comparatively inexpensive nature and of a strong and durable construction, having certain features of novelty and improvement permitting the drying operation to be performed in a substantially continuous and automatic manner without necessitating the exercise of any particular care or attention upon the part of the attendant, whereby important advantages and increased efficiency and convenience are attained in the actual use of the apparatus.

The invention consists in certain novel features of the construction, and combinations and arrangements of the several parts of the improved drying apparatus, whereby certain important advantages are attained and the apparatus is rendered simpler, less expensive and otherwise better adapted and more convenient for use, all as will be hereinafter fully set forth.

The novel features of the invention will be carefully defined in the claims.

In order that my improvements may be the better understood, I will now proceed to describe the same with reference to the accompanying drawings, wherein I have illustrated one embodiment of the invention and in which—

Figure 1 is a view in side elevation of an apparatus for drying sand constructed according to my invention; Fig. 2 is a front elevation of the structure shown in Fig. 1; Fig. 3 is a rear elevation of the same; Fig. 4 is an enlarged sectional view illustrating certain features of the chute supporting means which will be hereinafter referred to; and Fig. 5 is a transverse sectional view drawn to an enlarged scale and illustrating certain features of construction of the heating means.

In these views, 1 and 2 represent spaced A-shaped frame members of different relative heights joined or tied one to the other by means of crossed braces or connections 3, these members being formed of angle bars in the structure herein shown, and at the upper part of each of the said frame members 1 and 2 is secured a bearing member 4 in which is mounted a rockable or vibra-

tory shaft 5 which affords a support for the drying means as will be hereinafter explained.

In the structure herein shown it will be observed that the different relative heights of the frame members 1 and 2 serve to position the shaft 5 at an inclination for a purpose which will presently be apparent. Each of the bearing members 4 is provided with a depending rib 6 having a face contacting with a surface of the corresponding frame member 1 or 2 and such bearing member is held in place upon such frame member by rivets or other suitable fastenings 7 passed through the ribs 6 and the adjacent frame member.

At that side of each member 4 whereat the shaft 5 is upwardly inclined, said shaft is provided with a sleeve 8 fixedly held thereto and the side of each bearing member 4 adjacent to such sleeve 8 is provided with a ball race wherein are contained a series of balls interposed between such bearing member and the corresponding sleeve 8 as shown in detail in Fig. 4 so as to afford ball bearings which facilitate the rocking or vibratory movement of said shaft. In order to hold the shaft against endwise movement after the parts have been assembled, a nut or collar 10 is fixed to its lower end portion in position for contact against the side of the lowermost bearing member 4 opposite to the correspondingly positioned sleeve 8.

11, 11 represent alined bolsters supported upon the upper and lower sleeves 8, 8 of

shaft 5 to which they are secured at their central parts in such manner that each bolster has its opposite end portions extended beyond opposite sides of said shaft, and 12 represents a chute member formed from sheet metal or the like secured at its upper and lower parts upon the bolsters 11, 11 and extended at an inclination parallel with and above the shaft 5 so as to afford a channel along which the sand to be dried is adapted to be passed. An intermediate bolster 13 is provided for the support of the central part of the chute member 12, being secured to a sleeve 14 on shaft 5 substantially midway between the sleeves 8, 8. The chute member 12 being thus supported upon the bolsters which are fixedly secured to shaft 5 through the medium of sleeves 8 and 14, it will be evident that rocking or vibratory movement of said shaft will be imparted to the chute member to rock or oscillate the same in a lateral direction, and for imparting such rocking or vibratory movement to the parts I have shown the intermediate portion of the chute member provided with brackets 16 at its opposite sides to which are coupled the upper ends of pitmen 15 which are extended downwardly and pivotally secured to the opposite ends of a walking beam, 18 mounted for oscillation upon a shaft 19 and coupled by a link 20 with a crank disk 21 mounted upon a shaft 22

provided with a pulley 23 adapted to receive a belt or band whereby said shaft may be driven from any suitable source of power which may conveniently be a steam engine if steam is employed as a heating medium as in the apparatus herein shown.

The sand or other material to be dried is conveyed to the upper end of the inclined chute member 12 by means of a belt conveyer 31, as herein shown, and is delivered over the extremity of said conveyer to an inclined spreader 30 positioned at the upper end of the chute member 12 and adapted to receive the sand or other material discharged over the end of the conveyer 31 and to direct the same into the upper end of the inclined chute member. The spreader 30 is made gradually widened toward its lower part whereat the material to be dried is delivered to the chute member and its inclined surface over which said material passes is provided with spaced divergent ribs 32 which operate to spread the material laterally and evenly across the width of the chute member so that the drying operation may be more effectively conducted.

Within the chute member 12 and adjacent to the opposite upper and lower ends thereof are transversely extended double manifolds 24 and 25 connected with one another by two series of pipes 26 and 27 extended longitudinally along the inclined bottom of the

chute member. As herein shown, the pipes 27 which alternate between the pipes 26 and are of less diameter than said pipes 26, are closely adjacent to the inclined bottom of the chute member, while said pipes 26 are positioned at some distance from said bottom of the chute member whereby it will be seen that a plurality of grooves are produced between said pipes 26 extended lengthwise of the chute member and serving for the downward conveyance of the material to be dried in close contact with said pipes 26 and 27. The connection of the pipes 26 and 27 with the manifolds 24 and 25 may be effected in any desired manner but it has been found desirable to avoid the use of unions and to screw said pipes directly into the manifolds.

Discharging into the manifold 24 at the upper end of the chute 12 is a steam inlet connection 28 shown on the drawings as a flexible member leading from a suitable source of supply which may with advantage be the boiler for the operating engine, while the lower manifold 25 is in communication with the similar flexible discharge connection 29 from which condensation flowing downward through the inclined pipes 26 and 27 may be led back to the boiler of the engine in a well-known way.

By the construction and arrangement of the parts as above described, it will be seen that in the operation of the apparatus, the

material to be dried will be continuously supplied to the upper part of the chute member and being spread over the inclined surface thereof will be fed downward over the grooved heating surface afforded by the pipes 26 and 27, the circulation of the steam through said pipes serving effectively to dry such material during its descent, while at the same time the rocking or oscillatory movement imparted to the chute member by the pitmen 15 being directed laterally with respect to the travel of the material over the inclined drying surface, will operate to agitate the material and to assure an even spreading of the material transversely of the width of the chute and assist in feeding the same downward to the lower discharge end of said chute member and thereby materially increase the efficiency of the machine for drying.

At opposite sides of the longitudinally grooved surface of the chute member afforded by the pipes 26 and 27, said chute member is provided with raised longitudinally extended side walls 12' which effectively prevent the spilling of the material from the sides of the chute member when the same is rocked and since it has been found to be advantageous in some cases to regulate the rocking or oscillatory movement of the chute member, I have shown the rod 20 adjustably secured to the crank disk 21 as indicated at 33 in Fig. 1, so that the throw imparted by the crank disk to the walking beam may be varied.

It has been ascertained in the practical use of the apparatus constructed as above described that a considerable strain is exerted longitudinally of the machine and in order to resist this strain an inclined brace 17 is provided at the forward or discharge end of the apparatus, which brace as shown in the drawings is formed from spaced bars secured to the upper part of the frame 1 and extended downwardly therefrom at an outward inclination with their lower ends contacting with the surface whereon the apparatus is supported.

From the above description, it will be seen that the improved drying apparatus constructed according to my invention is of an extremely simple and comparatively inexpensive nature and is particularly well adapted for use by reason of the facility with which the drying operation is conducted and of the general increased capacity for drying and it will also be obvious from the above description that the apparatus is susceptible of some change without material departure from the principles and spirit of the invention and for this reason I do not desire to be understood as limiting myself to the precise formation and arrangement of the several parts of the apparatus, herein set forth, in carrying out my invention in practice.

Having thus described my invention, what I claim and desire to secure by Letters Patent is:

1. An apparatus of the character described having a chute member provided with an inclined drying surface adapted to be traversed by the material to be dried, a pivotal support positioned beneath the chute member whereon said member is adapted for rocking movement laterally with respect to the travel of the material over its inclined drying surface, and means for imparting lateral rocking movement to the chute member upon said pivotal support.
2. An apparatus of the character described having a chute member provided with an inclined drying surface adapted to be traversed by the material to be dried, bearings beneath the chute member, a pivotal support engaged with each bearing and operable to support the chute member for rocking movement laterally with respect to the travel of the material over its inclined drying surface, and means for imparting lateral rocking movement to the chute member upon said pivotal support.
3. A device of the character described having a chute member provided with an inclined drying surface adapted to be traversed by the material to be dried, a shaft extended lengthwise along the chute member, bearings whereon said shaft is supported for pivotal movement, and means connected with the chute member and operable to impart thereto rocking movement upon said pivotal support laterally with respect to the travel of the material to be dried along said inclined drying surface.
4. An apparatus of the character described having a chute member provided with an inclined drying surface adapted to be traversed by the material to be dried, pivotal supporting means for the chute member including a shaft extended centrally and beneath the chute member and lengthwise of its inclined drying surface and bearings for said shaft, and mechanism operable to rock the chute member upon its pivotal supporting means laterally with respect to the travel of the material to be dried over the inclined drying surface of the chute member.
5. An apparatus of the character described having a chute member provided with an inclined bottom affording a drying surface and having side walls extended above said inclined bottom at opposite sides thereof, means affording pivotal support for the chute member including a shaft extended centrally and lengthwise beneath the inclined bottom thereof and bearings for said shaft, and means for imparting rocking movement to the chute member laterally with respect to the travel of the material to be dried over said inclined bottom.
6. An apparatus of the character described having an inclined chute member adapted to be traversed by the material to be dried a shaft extended centrally and lengthwise beneath the bottom of the chute member, bearings for said shaft affording pivotal supports whereon the chute member is adapted for lateral rocking movement, a walking beam, means for imparting oscillatory movement thereto and pitmen extended from opposite ends of the walking beam to opposite sides of the chute member.
7. An apparatus of the character described having a chute member provided with an inclined drying surface adapted to be traversed by the material to be dried, and driven means operable to impart rocking movement to the chute member laterally with respect to the travel of the material to be dried over its inclined drying surface and including a device capable of adjustment to vary the extent of lateral rocking movement imparted to the chute member.
8. An apparatus of the character described having a chute member provided with an inclined drying surface adapted to be traversed by the material to be dried, and driven means operable to impart rocking movement to the chute member laterally with respect to the travel of the material to be dried over its inclined drying surface, and including a crank device having adjustable connection with the chute member and capable of operation to vary the extent of lateral rocking movement imparted thereto.
9. An apparatus of the character described having a chute member provided with raised side walls and having a series of contacting pipes adapted for the flow of a heating medium and extended side by side lengthwise of the chute member between said side walls and affording an inclined drying surface adapted to be traversed by the material to be dried, and means for supplying a heating medium to said pipes.
10. An apparatus of the character described having a chute member provided with a series of parallel inclined pipes extended in contact with each other, side by side lengthwise of the chute member and affording a longitudinally grooved inclined drying surface at the bottom thereof, and means for supplying a heating medium to said pipes.

In witness whereof I have hereunto signed my name this 22nd day of August 1910, in the presence of two subscribing witnesses.
